US0D1015742S

(12) **United States Design Patent** (10) **Patent No.:** **US D1,015,742 S**
(45) **Date of Patent:** **** Feb. 27, 2024**

(54) **LUGGAGE CASE**

(71) Applicant: **SHENZHEN YUANDAOYUAN INDUSTRY CO., LTD.**, Guangdong (CN)

(72) Inventor: **Jianhua Chen**, Guangdong (CN)

(73) Assignee: **SHENZHEN YUANDAOYUAN INDUSTRY CO., LTD.**, Guangdong (CN)

(**) Term: **15 Years**

(21) Appl. No.: **29/828,438**

(22) Filed: **Feb. 25, 2022**

(30) **Foreign Application Priority Data**

Jan. 26, 2022 (CN) 202230056012.1
(51) **LOC (14) Cl.** **03-01**

(52) **U.S. Cl.** ..... **USPC D3/279**

(57) **CLAIM**

The ornamental design for a luggage case, as shown and described.

DESCRIPTION

FIG. 1 is a front perspective view of a luggage case of the present disclosure;

FIG. 2 is a rear perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines shown in the drawings represent portions of the luggage case and form no part of the claimed design.

1 Claim, 8 Drawing Sheets
